UNITED STATES PATENT OFFICE.

PATRICK M. GRANT, OF CHICAGO, ILLINOIS.

FLUID PUMP.

1,414,463.

Specification of Letters Patent.

Patented May 2, 1922.

Application filed September 25, 1920. Serial No. 412,760.

To all whom it may concern:

Be it known that I, PATRICK M. GRANT, a citizen of the United States, residing at Chicago, in the county of Cook and State of Illinois, have invented certain new and useful Improvements in Fluid Pumps, of which the following is a specification.

The invention relates to fluid pumps and is shown as embodied in a small pump adapted to be operated by hand for compressing air for pneumatic tires of motor vehicles and other rubber tired carriages and the like.

It is the primary object of the pump to generally improve the construction of the operating parts including the intake and exhaust valve construction, pump base, the pump piston and the handle.

Other objects of the invention will appear from the following description which is directed to the preferred embodiment of the invention as depicted in the accompanying drawing forming a part of the specification, the novel features being more specifically pointed out in the appended claims.

In the said drawing, Fig. 1 is a sectional view through the handle, the barrel, the piston and the base of the pump taken on line 1-1 of Fig. 2, the latter being an elevation view of the pump taken at an angle of ninety degrees to the sectional view of Fig. 1. In both Figs. 1 and 2 a part of the barrel is broken away to shorten the same for illustration, and in Fig. 2 the lower end of the pump barrel is sectioned to disclose details of construction of the piston.

Figs. 3 and 4 are top plan and side elevation views respectively of the valves controlling inlet and exhaust ports of the pump.

In the design of the invention it has been the primary object to produce an efficient pump for pumping fluids, and especially air for the purpose of filling pneumatic tires as it is notorious that the average pump and especially hand pumps as furnished by motor car manufacturers at the present time are very inefficient and short lived. Therefore, the features of novelty of my improved pump consist largely in certain refinements giving greater efficiency to the parts and enabling them to operate with a continued degree of efficiency over a longer period than devices of this kind as heretofore produced.

Reference character 10 designates the pump barrel which may be constructed of any desired material as a cylindrical piece of uniformly constructed brass tubing, the

extremities of which are preferably screw threaded as at 10^a to take the top cap 11 and at 10^b to take the base casting 12, the latter like the cap 11 being provided with an enlarged opening screw threaded around its periphery co-operating with the threaded portions 10^a and 10^b of the pump barrel. For the purpose of providing a fluid tight connection between the lower end of the pump barrel and the pump base casting 12 a gasket 13 is preferably inserted so as to be interposed between the lower end of the barrel and the bottom of the concentric threaded portion in the base casting 12 when the barrel is screwed down to position therein. The base casting 12 I prefer to make as small and light as possible as it preferably contains the inlet and exhaust valved passages and is therefore made of an expensive and easily workable material as brass. It has heretofore been common to construct the foot engaging portions of the pump integral with the base casting 12 and where this is done the casting on account of the metal required becomes expensive and it is frequently not made strong or large enough to be efficient and durable. For these reasons I prefer to provide a special foot engaging portion for the base part 12 of the pump, which is accomplished by constructing a central downwardly projecting member 12^a cylindrical in form and screw threaded to take a central perforation, which will preferably be correspondingly screw threaded to form a durable connection, this part being designated generally by reference character 14 and being preferably formed from a suitable metallic channel bar, as illustrated in the sectional view of Fig. 1, and in side elevation in Fig. 2. A suitable locking nut 15 will be screwed in position on the lower or concave side of the channel piece 14, thus effectively and securely fastening the parts of the base together.

The gasket or washer 13, before referred to, of suitable flexible material as fiber, leather or rubber will have a central perforation, as indicated at 13^a registering with the vertical passage 12^b in the base casting 12, which latter communicates with a transverse passage 12^c, the latter passage extending in diametrically opposite directions from the vertical passage 12^b and terminating in offset or enlarged openings, each screw threaded and designed to furnish housings for accommodating the inlet and exhaust valves

and valve seats respectively. The opening constituting the inlet valve housing is surrounded by the screw threads designated by 12^a and the corresponding opening around 5 the housing for the exhaust valve by reference character 12^e. The opening or housing for the intake valve is closed by a screw threaded plug 16, the threads of which co-operate with threads 12^d of the base casting. 10 The plug 16 is provided with an enlarged central perforation 16^a designed to accommodate the stem of the valve closing the inlet port of the pump, the valve seat being formed at the inner extremity of the plug 16 15 as designated by reference character 16^b, and being in the form of a peripheral ledge elevated a short distance, as shown in Fig. 1, above the normal face of the end of the plug whereby an effective closure or seat will be 20 afforded for the flexible portion of the inlet valve. The latter, as stated, is of special construction and is in duplicate, one valve serving as a closure for the inlet port and another serving as a closure for the exhaust port. 25 The details of these valves are shown in Figs. 1, 3 and 4, and from an inspection of which it will be seen that in the preferred form of these valves a body portion or stem designated by reference character 17 is provided 30 of some suitable solid metal as brass, the same being angular in cross section and shown as cut from a hexagonal bar. One end of the stem member 17 is bored for a distance approximating one third the length 35 thereof and is screw threaded to take the suitable threaded screw 17^a, the latter being provided with the usual slot, as indicated to receive a suitable tool. A valve disk 18 is provided, the same having a central perforation adapted to register with the aforesaid 40 port and threaded opening in the end of the valve stem 17. The valve disk 18 is preferably provided at its outer periphery with angularly extending continuous webs, the web 45 on one side of the disk being continuous around the entire periphery of the disk to furnish a seat for a resilient disk or pad made of some suitable elastic material as leather or rubber composition designed to 50 assist the valve in forming an air tight closure with its seat.

An important feature of my improved valve resides in the manner in which I assemble the stem member 17 and the valve disk 18. This is secured by first turning off 55 a portion of the material at the valve disk end of the valve stem leaving a projection or peripheral central ledge as indicated by reference character 17^b. The height of the 60 peripheral ledge 17^b will preferably be about the normal thickness of the flexible disk of the valve designated by reference character 19, so that when the valve disk 18 is brought tightly in position with its hexagonal stem 65 17 the flexible member 19 of the valve will

not be injuriously compressed and hence caused to flatten out and gradually lose its efficiency. This construction is obviously beneficial alike for the valve at both inlet and exhaust ports and the valve disk 18 preferably has the outer peripheral flange or ledge on the side of the disk opposite the side to which the stem 17 is secured cut away at frequent intervals around its periphery, as indicated at 18^a, for the purpose of providing air passages to prevent the valve from obstructing the passage on the discharge side of the valve when the valve is held in the open position. At the discharge side of the passage 12^e in the base 75 the valve seat on the base is indicated by reference character 12^c, the same being formed similarly to the aforesaid seat 16^b. In this instance it will be noted that the valve seat is formed integrally with the base 80 casting 12 while the screw threaded plug closing this valve housing at the exhaust passage designated by reference character 20 is without a valve seat and both plugs 16 and 20 are formed of a length so that there 85 will be an ample space in the valve chamber for freedom of movement to the valves. The valve plug 20 like the plug 16 will be centrally perforated at 20^a and the perforation may be screw threaded to take a screw 90 threaded perforated nipple for a fluid hose designated by reference character 21.

The construction of the pump piston will 95 next be described.

A specially formed or machined piston 100 frame is provided, the same being somewhat smaller in diameter than the internal diameter or bore of the pump barrel 10 and same is designated generally by reference character 30. This piston construction is one of 105 the important features of my invention, which taken together with other improved features noted enables my improved pump to operate with much greater ease and efficiency than pumps of this type heretofore 110 produced and also to be more durable and last much longer in use. The piston frame 30 is centrally bored and screw threaded to take the threaded lower end of the piston rod 40, the latter passing into the pump barrel through the centrally perforated top cap 11, the said top cap being preferably perforated in the usual manner as at 11^a to prevent any back pressure on the non-working side of 115 the piston. The pump piston frame in order to be effective is provided with a packing or washer of suitable flexible material as leather, which may be cut from a flat disk and centrally perforated to take the piston rod 40 and then formed in substantially 120 the shape as indicated by the cross sectional view Fig. 1, this part being designated in the drawing by reference character 31. In order to furnish a suitable seat and housing in 125 the piston for the flexible washer or gasket 130

31 I give the same a special formation by cutting away the upper surface of the part, as indicated, so that there will be first left a peripheral ridge or ledge 30^a surrounding 5 the threaded central opening for receiving the piston rod and on the exterior of the ledge 30^a the material of this part will be cut away a sufficient distance to accommodate the approximate thickness of the pump 10 washer 31, this cutting being in the form of a groove, as indicated at 30^b, thus leaving a concentric peripheral ridge or rib designated by reference character 30^c around the top side of the piston frame. The outer top 15 periphery of the frame 30 on the exterior of the concentric ridge 30^c will be rounded so as to permit the downward curvature of the washer 31 and the material of the piston frame number 30 will be turned off or reduced 20 in diameter in a downward direction to a point a short distance above the lower extremity of the piston frame, thus leaving a peripheral lower rib or ledge, as indicated by reference character 30^d. For the purpose 25 of securely holding the piston washer or gasket 31 in its normal working position I provide a circular upper plate 32 which will be of a slightly less diameter than the internal bore of the pump barrel so as to 30 escape contact with the walls of the pump barrel but at the same time to overlie the flexible piston washer or gasket 31 and retain the same in its proper working position. 35 In assembling the pump piston on the lower end of the piston rod a locking nut of hexagonal or other suitable form as indicated by reference character 33 will be first screwed to the approximate upper limit of the lower threaded end of the piston rod 40 and the 40 perforated follower ring 32 which has its perforation larger than the diameter of the piston rod will be slipped over the threaded part in contact with the nut 33. The piston frame with the flexible washer or gasket 31 45 in position with the central opening therein surrounding the internal peripheral rib 30^a may then be screwed into position on the lower end of the piston rod until the lower end of the rod is brought forcibly into contact with the bottom of the bored or threaded central opening therein. The locking nut 33 may then be screwed downwardly upon the follower plate which will force the material of the flexible gasket downwardly into 50 the peripheral curve 30^b in the top of the piston frame and will cause the upstanding peripheral rib 30^c to compress and cut into the gasket a certain amount, as indicated in the drawing, so that there will be a bead 55 of material formed in the piston washer or gasket adjacent the upstanding central ledge or rib 30^a at the top tending to hold the washer 31 in position. At the same time 60 the outer periphery of the washer or gasket 31 will be forced downwardly into the hous- ing formed between the reduced peripheral part of the piston frame and the inner wall of the pump barrel so that in this manner the piston washer or gasket will approximately fill the space between the follower 70 ring 32 around the peripherally reduced part of the piston frame and above the lower peripheral ledge 30^d thereof. The fact that the upper peripheral edge of the piston frame is rounded will prevent any cutting 75 of the piston washer or gasket and it will be seen that the housing for the active part of the washer thus formed will be very effective in holding the leather or other flexible material, of which this part is made, in its 80 proper working position, so that the only strain that will fall upon this part which receives the hardest usage of any part of a pump will be the duty of frictionally contacting with the wall of the pump barrel 85 as the part is effectively and securely retained between the follower plate 32 at the top and lower peripheral ledge 30^d at the bottom of the piston frame. Furthermore the ledge or central peripheral rib 30^a will 90 prevent any undue pressure on the follower plate from cutting or injuring or unduly forcing outwardly the material of the flexible washer or gasket and the locking rib 30^c will also result in the formation and 95 retention of the thickened peripheral bead in the flexible washer or gasket at the top thereof, which will tend to cause the part to remain in its proper working relation during the entire life of the frictional part of 100 the flexible washer or gasket.

Obviously, in order for a pump piston to be effective it must furnish an approximately complete closure with the walls of the pump barrel on the down or active stroke 105 of the piston and this can only result when the flexible washer or gasket 31 is in contact throughout the periphery of the piston with the pump barrel walls.

One of the common defects in pumps of 110 this character having flexible washers has been that while the pumps are comparatively new and the gaskets or washers are new there will be satisfactory contact between the piston washer and the pump barrel but after the pump has been used for a time and the washer tends to lose its elasticity or flexibility the skirt or effective portion of the washer is found in practice to seat around the piston frame so that the 115 washer may remain entirely or partly out of contact around its periphery with the wall of the pump barrel resulting in leakage and decreased efficiency in the pump. In order to overcome this defect and difficulty 120 with pumps of this type I provide two improved means which I find in practice insure at all times that the pump washer or gasket will remain in contact throughout its 125 periphery with the pump barrel.

The first of these means comprises a peripheral groove designated by reference character 30° which is cut around the reduced portion of the piston frame about 5 midway between the upper and lower edges thereof and at a point that falls beneath the skirt or depending portion of the piston washer 31 when the latter is in its proper working position; the groove, however, being cut so that it will be somewhat above the lower extremity of the washer so that any air pressure within the groove 30° will be effective to force or crowd the skirt or depending portion outwardly in contact with 10 the pump barrel. I provide a plurality of perforations 30^g in the lower end of the piston frame. These perforations 30^g are bored approximately parallel with the central opening in the washer frame, which is 15 threaded and takes the piston rod and they each communicate with the peripheral groove 30° so that as the piston is forced toward the lower end of the pump barrel on its effective or pressure stroke the compression 20 of the air beneath the piston through the passages 30^g and 30° will tend to expand the piston washer and insure contact with the walls of the pump barrel from which it results that the harder the piston is worked 25 the closer will be the contact as long as the piston washer or gasket remains in effective working condition. In the use of a piston constructed as described, I have found in some cases that after the pump has been in 30 use for some time the flexible washer or gasket 31 may tend to seat in contact with the reduced part of the piston frame and remain so effectively in contact therewith that even the pressure of the air through the 35 passages 30^g and 30° might not be sufficient to expand the piston, and my second improved feature consists in the provision of a thin metallic ring or band the material of which is entirely severed at one point in its periphery and will underlie the inner vertical 40 wall of the flexible washer and on the outer periphery of the reduced part of the piston frame, as indicated by reference character 34, this part being shown in section in Fig. 1 45 and in an enlarged perspective in Fig. 5. This ring or band 34 which will be readily expandable will preferably be made of brass or other suitable non-corroding refined metal so as not to be readily oxidizable will I find 50 be hence effective in preventing sticking of the washer 31 and will insure that the latter will be expanded on each downward effective stroke of the piston, greatly increasing the effectiveness of the pump. In order to prevent any undue pounding of the piston 55 against the top cap plate 11 of the pump barrel I provide the coil spring 35 which will act as a cushion upon the contact of the piston with plate 11 at the upper limit of its 60 stroke.

Another important feature of my pump resides in the construction of the handle which is made of a piece of cylindrical metallic tubing designated by reference character 50. Heretofore handles of this description have been attached to pump pistons by perforating the cylindrical handle member and passing the upper extremity of the piston rod out through the top side of the handle where it is secured in position by suitable means as a lock nut. This construction results in placing the nut in the upper end of the piston rod in a position where it is in contact with the hand of the operator and as the pressure in operating 70 the pump is applied on the upper end of the handle I prefer to construct this part so that the upper surface thereof will be smooth, which I accomplish by placing on the interior of the hollow cylindrical handle 50 a cylinder or plug of less length than the handle as indicated by reference character 51, Fig. 1, the same being bored and threaded as indicated at 52 to take the upper threaded end of the piston rod. The plug 51 will preferably be a loose sliding fit on the interior of the hollow handle member 50 and there will be an opening in the wall of the cylindrical member 50 large enough to permit the upper threaded end of the piston rod to pass readily therethrough so that it may engage the threaded opening 52 in the plug 51. In order to lock the piston rod and the handle securely together I prefer to provide a plate 53 which may be 80 formed as a special casting to have its upper surface curved to furnish a seat for the cylindrical handle member 50 or if desired, as illustrated in Figs. 1 and 2, the part 53 may be cut from a piece of channel bar and centrally bored to permit the ready passage of the upper threaded end of the piston rod therethrough. The upper thread of the piston rod will be provided with a suitable locking nut 54 and a spring locking washer 85 55 will preferably be inserted between the nut 54 and the plate 53. By this construction it will be seen that when the plug 51 is on the interior of the handle the upper end of the piston rod may be passed through 90 the perforation in the handle and into the threaded opening 52 in the plug 51 and screwed into the plug. After this is done by adjusting the nut 54 on top of the washer 55 the plate 53 may be locked in close contact so that the wall of the handle 50 will be 95 securely held where locked in position between plug 51 and plate 53 thus giving the handle a rigid attachment with the piston rod which will not have any tendency to 100 work loose in use by reason of the locking character of the washer 55 and the nut 54. At the same time it will be seen that the upper side of the handle will be smooth so as 105 not to injure the hand of the operator. 110

The improved pump as herein described has been found by me to be highly efficient. It is comparatively economical to manufacture and offers advantages not heretofore found in hand pumps used for a variety of purposes in compressing air as for the inflation of pneumatic tire tubes and the like. The fact that each of the several parts of the pump are all readily detachable makes it possible for the user of the pump to readily replace any worn parts, as for example the pump piston washers, the valve seating gaskets, etc., thus adding greatly to the life and effectiveness of the pump.

15 I claim:

1. In a pump, the combination with a pump barrel of a piston therein, a base member to which the said barrel is attached, there being a passageway in the base member communicating with the pump barrel and valve mechanism in the said passageway comprising a valve seat, a valve stem in cross section adapted to be guided in said passageway adjacent the valve seat, a valve plate secured to the said stem, a resilient member carried by the valve plate, and means for locking the said valve plate and stem together.

2. A fluid pump comprising a pump barrel, a reciprocating piston in said barrel, a pump base secured to one end of the pump barrel, there being a passageway in said pump base leading to an enlarged threaded passageway intersecting the outer surface of the pump base, a perforated screw threaded plug adapted to close the said enlarged screw threaded opening in said base, a valve seat carried by the said plug and surrounding the perforation therein, and a valve having a valve stem carried by the perforation in the said plug, the said valve being adapted to co-operate with the said seat on the plug to close the perforation in the plug on the discharge stroke of said piston.

45 3. In a fluid pump the combination with a pump barrel of a piston frame having a peripheral groove, a flexible washer surrounding said groove, there being perforations in the piston frame leading from the compression side of the piston frame to the said groove to expand said washer during the compression stroke of said piston frame.

4. In a fluid pump the combination with a pump barrel of a reciprocating piston rod in the barrel and a piston carried thereby, the said piston comprising a frame secured to the piston rod, there being a centrally bored piston frame adapted to take the screw threaded end of the piston rod, a lock nut on the threaded portion of the piston rod, a peripheral rib on the piston frame, a perforated follower plate adapted to be secured between the said nut on the piston rod and the said piston frame, and a flexible piston washer

ed to surround the said rib on the piston frame and being secured in position between the said follower plate and frame.

5. In a fluid pump the combination with a pump barrel and a piston rod of a piston in said barrel carried by said rod and comprising a piston frame secured to the said rod, there being a groove formed peripherally in said frame for the reception of a flexible piston washer, a washer filling said peripheral groove in the piston frame, and an opening having one extremity adjacent the inner wall of the flexible piston washer and its other extremity on the face of the piston frame adjacent the compression side thereof whereby to expand the washer upon the compression stroke of the piston.

6. In a fluid pump the combination with a pump barrel of a piston therein comprising a frame having a centrally bored opening therein adapted to receive a piston rod, there being a reduced portion of said frame adapted to accommodate the peripheral edges or skirt of a flexible piston washer, said piston frame being provided with a plurality of openings leading from the compression side of the piston frame to a groove adapted to underlie the skirt or outer peripheral edge of the flexible piston washer, whereby to expand the latter upon the compression stroke of the piston, a peripheral ledge around the centrally bored opening in the piston whereby to protect the flexible washer, a follower plate and a lock nut for engaging the threaded portion of the piston rod to secure the follower plate and the piston rod together and to retain the flexible piston washer in operative relation to the piston frame.

7. In a fluid pump the combination with a pump barrel of a reciprocating piston rod and a piston carried thereby and adapted to co-operate with said pump barrel, said piston comprising a piston frame having a central bore screw threaded to take the threaded end of the piston rod, the body portion of the piston frame being reduced whereby a ledge is formed at the lower edge of the piston frame forming a part of a housing for the piston washer, there being a groove formed peripherally around the reduced part of the piston and adapted to underlie the piston washer together with an air passage leading from said groove to the compression side of the piston frame, whereby the pressure of air on the compression side of the piston frame will tend to expand a flexible piston washer carried around the reduced part of the piston frame, an elastic and expansible metallic ring adapted to overlie the said peripheral opening around the reduced portion of the piston frame whereby to prevent the flexible piston washer from sticking to the piston frame, a flexible piston washer in position around the reduced part of the

piston frame, and a follower plate secured on the piston rod in engagement with the said flexible piston washer, whereby to retain the same in its effective operative relation with the piston frame.

8. In a fluid pump the combination with a pump barrel and a piston therein of a piston rod secured to the piston, a handle for operating the piston rod, a pump base secured to the lower extremity of the pump barrel comprising a casting provided with valved air passages, a threaded projection or trunnion on the lower edge of the casting and formed integral therewith, a foot base member secured to the latter and comprising a section of channel iron having the extensions thereof extending downwardly with a central perforation screw threaded on the said screw threaded projection or 20 trunnion, there being a lock nut on the said trunnion engaging the channel foot member between the downwardly projecting extensions thereon.

9. In a fluid pump the combination with a pump barrel of a piston, a piston rod and an operating device or handle secured to the said piston rod and comprising a tubular member having a perforation in one wall thereof through which perforation a threaded end of the piston rod is adapted to be loosely passed, a plug adapted to be contained in the interior of the said tubular member and having a threaded socket therein adapted to co-operate with the threaded end of the piston rod, and a screw threaded locking device adapted to co-operate with a threaded portion of the piston rod on the exterior of the tubular member to lock

rigidly upon the threaded end of the piston rod the tubular handle member and the aforesaid plug therein.

10. In a fluid pump the combination with a pump barrel and a piston of a piston rod secured to the piston and having the extremity thereof on the exterior of the pump barrel screw threaded, a tubular handle member provided with an opening in one wall thereof adapted to permit of the insertion loosely therethrough of the threaded end of the piston rod, a plug adapted to be inserted on the interior of the tubular handle member and having a screw threaded socket therein adapted to register with the opening in the wall of the tubular handle member and to take the threaded end of the piston rod, a perforated supporting member having an opening in the wall of the tubular member and having a concave surface thereon adapted to co-operate when assembled on the piston rod with the convex outer surface of the tubular handle member, and means for locking the aforesaid plug, the tubular handle member and the supporting member in rigid relation on the threaded end of the piston rod comprising a spring lock washer and a screw threaded nut below the said supporting member on the threaded upper end of the piston rod.

In testimony whereof I have signed my name to this specification, in the presence of two subscribing witnesses, on this 20th day of September, A. D. 1920.
